Specification of Letters Patent. Patented Mar. 4, 1919.

Application filed May 19, 1917. Serial No. 169,620.

To all whom it may concern:

Be it known that I, WARD S. IRELAND, a citizen of the United States of America, a resident of the city of St. Louis, State of Missouri, have invented certain new and useful Improvements in Shorthand-Machines, of which the following is a full, clear, and exact description, reference being had to the accompanying drawings, forming a part of this specification.

My invention relates to improvements in shorthand machines. Prior to this invention, shorthand machines have been provided with means for feeding a continuous strip of paper, which unwinds from a roll and passes to printing devices whereby a continuous series of characters are printed upon the paper. Owing to the peculiar requirements of a shorthand machine, it is a decided advantage to use a very long strip of paper so the writing may be continued for a considerable period of time without frequent interruptions, and heretofore the paper has been firmly wound in a compact mass around a core. While a paper supply in the form of a small compact roll is highly desirable in a shorthand machine, considerable difficulty has been experienced in handling such paper after it unwinds and passes from the machine. The paper is primarily firmly curled around the axis of the roll, and after passing from the roll it tends to return to a spiral or curly condition. If torn from the machine in comparatively short strips, the paper would be in the form of small curls and quite difficult to handle. On account of the tendency of the paper to recurl, the paper handling devices of shorthand machines have not been entirely satisfactory.

Therefore, one of the objects of this invention is to produce a shorthand machine adapted to unwind and feed the paper from a roll, and also adapted to obviate the labor of handling curly strips of paper. With this object in view the machine includes means for uncurling the paper after it passes from the supply roll. Another object is to produce an uncurling device associated with other elements of a typewriting machine in such a manner that the desired uncurling action is obtained without impairing the action of the machine. Another object is to produce a typewriting machine

having a paper straightener which becomes effective upon the operation of the printing keys.

After being unwound, the paper tends to return to the curly condition in which it was held in the spirally wound roll, and since each coil of paper in the roll differs in diameter from the other coils, the paper passes from the roll in a decidedly non-uniform condition. The tendency of the paper to recurl gradually increases during the unwinding operation. Hence, an uncurling device designed to uncurl the small coils of paper near the center of the roll will not necessarily produce the same effect upon the larger coils. It may recurl instead of straightening the larger coils; or, if designed to properly uncurl the larger coils, the device may fail to uncurl the smaller coils. An object of the invention is to produce an efficient uncurling device capable of straightening all of the paper passing from the supply roll. To illustrate this feature of the invention, I have shown and will hereinafter more fully describe means for placing the paper under tension, and an uncurling device for straightening the tensioned paper. The effect of the uncurling device varies in accordance with the degree of tension under which the paper is held, and the tension is automatically increased as the roll becomes smaller in diameter. By gradually increasing the tension during the unwinding operation, and subjecting the paper to the action of an uncurling device, all of the paper passing from the roll is placed in an absolutely straight condition.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a longitudinal section of a shorthand machine constructed in accordance with my invention.

Fig. II is a transverse section taken approximately on the line II-II, Fig. I.

Fig. III is a detail view of the paper feeding roll.

Fig. IV is a section taken approximately on the line IV—IV, Fig. III, showing the driving clutch whereby a step by step movement is imparted to the paper feeding roll.

Fig. V is a section on line V—V, Fig. III, showing the retaining clutch associated with the paper feeding roll to prevent retrograde movement.

Fig. VI is a fragmentary plan view of the rear portion of the machine.

Fig. VII is a side elevation of the rear portion of the machine, a portion of the housing being broken away to show the frictional detent associated with the paper feeding roll.

To illustrate the invention, I have shown a shorthand machine provided with printing keys 1 secured to key levers 2, the latter being pivotally supported by a pivot rod 3 (Fig. I). Each key lever 2 is provided at its rear end with an upwardly extending printing hammer 4 (Fig. I) adapted to cooperate with a type bar 5 having type characters 6 on its bottom face. An inking ribbon 7 passes between the printing hammers 4 and the type 6. Each key lever 2 is arranged directly below a restoring spring 8 (Fig. I) and the restoring springs yieldingly hold the key levers in their non-printing positions. The strip of paper 9 passes downwardly from a supply roll 10, under a small uncurling rod 11, thence upwardly and over a paper feeding roll 12, downwardly through an inclined passageway 13 (Fig. I) and then rearwardly to a discharge opening at the rear of the machine. The paper travels between the printing hammer 4 and inking ribbon 7 before it reaches the rear end of the machine.

When a printing key is depressed, its key lever 2 turns about the axis of the pivot rod 3 (Fig. I), and the printing hammer 4 at the rear of the key lever moves upwardly to force a portion of the paper onto the inking ribbon 7, at the same time forcing the ribbon onto one of the type characters 6. The printing keys may be operated independently of each other to print selected characters, and several keys may be operated simultaneously to print a line of characters, as is well understood in this art. The characters are usually printed line by line, a complete word or syllable being printed during each key operation. The strip of paper is advanced one step in response to each key operation.

The paper feeding device comprises a universal bar 14 (Fig. I) arranged over the key levers at a point in front of the printing hammers 4 and fixed to a bell crank lever 15, the latter being pivotally supported by the pivot rod 3. The upwardly extending arm of this bell crank lever 15 is notched

to receive a pin 16 (Figs. II, III and IV) projecting from the oscillatory drive member 17 of a paper feeding clutch. This drive member 17 is loosely mounted in a driven clutch member 18, the latter being rigidly secured to one end of the paper feeding roll 12. The universal bar and its bell crank lever 15 are oscillated by the key levers, and the drive clutch member 17 oscillates in response to movements of the universal bar, so as to impart a step by step movement to the paper feeding roll 12. When the oscillatory drive member 17 turns in the direction indicated by the arrow in Fig. IV, the small spring pressed rollers 19 are firmly clamped in the wedge-shaped spaces between said drive member and the driven clutch member 18. Movement is then transmitted from the universal bar, through the drive member 17 and rollers 19, to the driven clutch member 18. The paper feeding roll 12 is secured to the driven clutch member 18 so as to advance one step when the oscillatory drive member 17 turns in the direction indicated by the arrow in Fig. IV. During the reverse movement, when the drive member 17 moves oppositely to the direction indicated by the arrow in Fig. IV, the small rollers 19 tend to move into the wide ends of the wedge-shaped spaces, and they do not transmit movement to the driven clutch member 18. In response to the oscillatory movements of the universal bar and drive clutch member 17, the paper feeding roll 12 turns step by step in the direction indicated by the arrow in Fig. IV.

To positively prevent retrograde movement, a stationary clutch member 17' (Figs. III and V) is arranged within a rotary clutch member 18' secured to one end of the paper feeding roll 12. A pin 20 extending from the stationary clutch member 17', is secured to a stationary side frame 21. Spring pressed, rollers 19' are arranged in the wedge-shaped spaces between the stationary clutch member 17' and the rotary clutch member 18'. These small rollers 19' allow the feed roll 12 to turn freely in the direction indicated by the arrows in Figs. IV and V, but if an effort is made to reverse the direction of movement, the small rollers 19', by tending to move toward the points of the wedge-shaped spaces will cooperate with the stationary clutch member 17' to prevent such retrograde movement.

The paper is forced into firm engagement with the feed roll 12 by means of a pressure roll 23 (Fig. I). The small uncurling rod 11 (Figs. I and II) is reduced at its ends to form journals which are rotatably mounted in bearings 24. At this small rotatable rod 11, the strip of paper 9 is turned abruptly in a direction opposed to the direction in which it was wound in the roll. It will also be noted that the rod 11 is so located that

a large area of the feeding roll 12 will contact with the strip of paper at a point between said rod 11 and the pressure roll 23.

The roll of paper 10 is secured to a core 5 25 (Figs. I, VI and VII) provided with journals 26, the latter being mounted in suitable bearings, as shown most clearly in Fig. VI. These bearings are open at the top so that the roll of paper and its core may be 10 15 readily applied to or removed from the machine. 27 designates friction members, in the form of latch dogs, and 28 designates springs which force these members 27 into frictional engagement with the journals 26. 15 The friction members, or latch dogs, 27 detachably secure the roll of paper to the machine, and they also form very important parts of the paper straightener.

The friction members 27 continuously and 20 uniformly engage the journals 26 at a fixed distance from the axis of the roll of paper, and this distance is not changed by variations in the diameter of the roll of paper. These friction members tend to prevent the 25 roll of paper from turning, and upon the operation of the paper feeding device, the paper is pulled onto the small uncurling rod 11 while held under tension by the friction members 27. By holding the paper under tension and pulling it onto the uncurling rod 11 in the manner illustrated, the paper is uncurled and fed from the machine in an absolutely straight condition. To obtain the desired uncurling action, the tension 35 of the paper is preferably gradually increased as the roll of paper becomes smaller in diameter, and this gradually increasing tension can be obtained without changing the location of the friction members 27, and 40 without changing the tension of the springs 28 which force said members 27 into frictional engagement with the journals 26.

In this connection it is important to note 45 that the energy for unwinding the roll of paper is transmitted from the paper feeding device to the periphery of the roll, through the medium of the strip of paper. At the beginning of the unwinding operation, the pulling action of the roll of paper 50 is exerted from a point remote from the axis of the roll, and, as the roll decreases in diameter, the point at which the pulling action is exerted gradually approaches said axis. The roll of paper is analogous to a pivotally 55 supported lever arm which gradually decreases in length, and the strip of paper may be considered as a means for connecting the free end of such a lever arm to a source of energy. Owing to the constantly changing 60 leverage, the force of the pulling action at the roll of paper must constantly increase during the paper feeding operations, for the energy required to pull the paper a fixed distance depends upon the distance from the 65 center of the roll to the periphery, and as

the diameter of the roll gradually decreases, the force of the pulling action must be constantly increased. The resistance offered by the friction members 27 does not change, the gradual increase in the tension of the 70 paper being due to the fact that the roll gradually decreases in diameter and the paper must then be pulled more firmly to overcome the resistance offered by the friction elements. 75

The successive feeding operations gradually reduce the diameter of the roll of paper and the tension of the strip of paper gradually increases in strict accordance with the gradually increasing diameter of the paper 80 to be uncurled. As previously suggested, the object in gradually increasing the tension of paper is to gradually increase the force of the uncurling action, so as to positively straighten all of the paper passing from the 85 roll. The tendency of the paper to recurl gradually increases as the roll becomes smaller in diameter, and this lack of uniformity is compensated for by the means for gradually increasing the tension of the 90 paper.

From the foregoing, it will be understood 95 that the new paper straightener preferably comprises a combination of three very important elements which coöperate with each other to produce a unitary result, these elements being the uncurling member 11 located at a point where the paper is turned abruptly, a paper feeding device for pulling the paper onto said uncurling member, 100 and a retarding member coöoperating with the roll of paper to offer a gradually increasing resistance to the paper feeding device, the tension of the paper being increased as the roll of paper decreases in diameter. 105

It is also important to observe that the printing keys are operated very rapidly. To obtain the necessary speed, the operator must strike and depress the keys very quickly. As a consequence, the key-actuated 110 paper feeding device jerks the paper onto the small uncurling rod, instead of moving the paper slowly. The quick, firm jerks resulting from the ordinary rapid key operations, cause the fibers of the tensioned paper 115 to be strained or broken at frequent intervals at the small uncurling rod 11, and this action very materially increases the effectiveness of the paper straightener. The paper is strained to a degree beyond its elastic limit, and it does not tend to spring back or return to a curling condition. 120

The roll of paper 10 moves so quickly in response to the rapid key operations, that it continues in motion at the end of each operation. This continued movement, due to the momentum of the roll of paper 10, loosens the strip of paper at the uncurling rod 11. During the next key operation, the quick action of the paper feeding device will take 125 130

up the slack and then suddenly jerk the paper onto the uncurling rod, so as to strain or break the curly fibers, at the same time bending the tensioned paper in a direction 5 reverse to the direction in which it was wound in the roll.

The paper is straightened very effectively without materially increasing the power at the finger keys. At the beginning of each 10 key operation, the universal bar and paper feeding rolls are actuated to take up the slack in the paper, very little power being required, and so the finger key continues its downward movement, the momentum of the 15 universal bar and feeding rolls aiding the operator in jerking the paper onto the uncurling rod and pulling the tensioned paper. Owing to these conditions, the quick-acting 20 paper straightener can be driven by the finger keys so as to obtain highly desirable results, without appreciably increasing the load or strain at the operator's fingers, and this is important, for the keys must move 25 freely and quickly when struck by the fingers. If the paper was uncurled by a continuous, uniform pulling and bending operation, the paper would not be loosened and then jerked onto the uncurling rod, and the additional power exerted by the operator's 30 fingers would be uniform and continuous during the entire downward stroke of the key.

By subjecting the paper to the action of the combination of elements herein shown, 35 the tendency to recurl can be eliminated without using a blade or a noisy frictional scraper on the surface of the paper. The uncurling member 11 preferably rotates freely in response to the jerks to which the 40 tensioned paper is subjected.

I claim:—

1. In a shorthand machine adapted to receive a roll of paper, a paper straightener comprising a paper feeding device for unwinding the paper and feeding it from the roll, an uncurling member onto which the paper is pulled by said paper feeding device, said parts being so arranged that the paper is turned abruptly at said uncurling member, retarding means coöperable with the roll of paper to offer a gradually increasing resistance to the paper feeding device, the tension of the paper at said uncurling member being increased as the roll decreases in 55 diameter, and printing keys whereby the paper feeding device is actuated intermittently to feed the paper step by step, the tensioned paper being jerked firmly and quickly onto the uncurling member in 60 response to the key operations.

2. In a shorthand machine adapted to receive a roll of paper, a paper straightener comprising a paper feeding device for unwinding the paper and feeding it from the roll, an uncurling member onto which the 65 paper is pulled by said paper feeding device, said parts being so arranged that the paper is turned abruptly at said uncurling member, retarding means coöperable with the roll of paper to enable said paper feeding device to place the paper under tension at said uncurling member, a universal bar for actuating said paper feeding device, and finger keys whereby the universal bar is actuated intermittently to feed the paper 70 step by step, the tensioned paper being jerked firmly and quickly onto the uncurling member in response to the operations of said finger keys and universal bar.

3. In a typewriting machine, a paper support including a core adapted to receive a roll of paper, and a paper straightener comprising an intermittent paper feeding device whereby the paper is unwound from the roll and fed step by step, an uncurling 80 member onto which the paper is pulled by said intermittent paper feeding device, said parts being so arranged that the paper is turned abruptly at said uncurling member, and friction members yieldingly fitted to 85 said core so as to detachably secure the core and roll of paper to the machine, said friction members also coöperating with the roll of paper to offer a gradually increasing resistance to the paper feeding device, the tension of the paper at said uncurling member 90 being increased as the roll decreases in diameter.

4. In a typewriting machine, a paper support including a core adapted to receive a 100 roll of paper, said core being provided with journals at its ends, and a paper straightener comprising an intermittent paper feeding device whereby the paper is unwound from the roll and fed step by step, an uncurling member onto which the paper is pulled by said intermittent paper feeding device, said parts being so arranged that the paper is turned abruptly at said uncurling member, and friction members yieldingly fitted to said journals so as to detachably secure the core and roll of paper to the machine, said friction members also coöperating with the roll of paper to offer a 105 gradually increasing resistance to the paper feeding device, the tension of the paper at said uncurling member being increased as the roll decreases in diameter.

WARD S. IRELAND.
